UNITED STATES PATENT OFFICE.

CHARLES F. MASSEY, OF CHICAGO, ILLINOIS, ASSIGNOR TO C. F. MASSEY COMPANY, OF CHICAGO, ILLINOIS, A CORPORATION OF ILLINOIS.

COLLAPSIBLE CORE FOR CONCRETE PIPES.

1,101,204.

Specification of Letters Patent. Patented June 23, 1914.

Application filed January 30, 1913. Serial No. 745,054.

To all whom it may concern:

Be it known that I, CHARLES F. MASSEY, a citizen of the United States, and resident of Chicago, in the county of Cook and State of Illinois, have invented certain new and useful Improvements in Collapsible Cores for Concrete Pipes, of which the following is a specification.

My invention relates to cores for concrete pipes and contemplates improved features of construction, arrangement and operation. Heretofore in the manufacture of concrete pipes sectional cores were used, these cores being set up piece by piece and fitted together in a mold, concrete or cement then poured in, and the core sections then removed piece by piece after setting of the cement. More or less difficulty was experienced in accurately fitting the core parts together and a great deal of time was consumed in building up and in withdrawing the core.

Among the important objects of my invention are therefore to provide a core in the form of a unitary structure which can be quickly and readily inserted in a mold and withdrawn therefrom; to provide a core of sheet metal and to provide improved means for automatically expanding the core when inserted in the mold and to cause collapse thereof and withdrawal from the formed concrete pipe upon withdrawal movement of the core; more in detail to provide a core in the form of a sheet metal shell bent to cylindrical form and to provide wedge mechanism for coöperating with the ends of the shell and to provide improved toggle mechanism automatically controlled upon insertion of a core in a mold to cause a wedge to be forced between the shell ends, and to be withdrawn from said ends upon extraction of the core to allow collapse of the core; to provide locking mechanism for positively locking the shell ends in expanded position while the cement material is being poured and worked in; and in general to provide a simple yet efficient collapsible core which may be used in the construction of concrete pipes in a factory or which can be used for progressive building of conduit or piping directly in the trenches where such conduit or piping is to be used.

In the accompanying drawings which show the various features of the invention

Figure 1 is a vertical elevational view of a molding structure showing the core and mold frames in vertical diametral section, and showing the wedging mechanism in alternate position in dotted lines; Fig. 2 is 60 a plan view of the molding structure when the core is fully expanded; Fig. 3 is a plan view of the core structure showing the relative positions of the parts just after withdrawal of the wedge from between the core 65 shell ends; and Fig. 4 is an enlarged sectional view taken on plane 4—4, Fig. 1.

The core is in the form of a shell 10 of preferably boiler plate bent into circular or elliptical form as shown. Running full 70 length of the ends of the shell and secured thereto as by riveting or welding are the angle bars 11 and 12, these bars being secured to the inner side of the shell with their flanges 11' and 12' extending inwardly. Preferably running full length of the shell and secured to the inner side thereof between its ends is a T-bar 13 whose web 75 13' extends radially inwardly. For controlling expansion and collapse of the core 80 toggle actuated wedge mechanism is provided, the wedge being in the form of a channel beam 14 is caused by toggle mechanism to be forced between the flanges 11' and 12' of the angle bars, thus expanding 85 the shell, the flanges 11' and 12' being preferably deflected outwardly a distance so that the wedge channel can more readily enter 90 between the flanges. A plurality of toggle link sets T are provided connected at intervals with the wedge channel, each set comprising a link 15 pivoted at its outer end to the web 13' of the T-bar and a companion link 16 pivoted to a lug 17 extending inwardly from the web of the wedge channel. The inner ends of the links of each set are pivoted together and to a toggle bar 18 extending centrally full length of the shell. When this bar is raised the wedge channel 95 is moved toward the T-bar and is withdrawn 100 from between the angle bars so that the shell ends may come together, and when the toggle bar is moved downwardly and the links of the sets are brought into parallelism the wedge channel is again forced between the 105 angle bars and the shell expanded.

Referring to Fig. 1, 19 represents a mold frame with which the core coöperates to form the mold for receiving the concrete material. This mold frame is constructed 110

for casting culvert pipes, its lower end 20 being expanded to form a joint flange. This mold frame is set on a suitable foundation 21 about the lower flange 22 of a ring 22 set on the foundation. The core shell is then lowered through the mold frame to rest on the foundation with its lower end within the ring 22. The toggle bar 18 is preferably provided with an eye 23 at its upper 10 end so that it may be readily suspended from a crane. When the core shell is thus suspended, the weight of the shell will cause collapse of the toggle members so that the shell ends are free, as indicated in dotted 15 lines in the figures, and when the shell comes to rest on the foundation the toggle bar is then forced downwardly to actuate the toggle members to insert the wedge channel between the shell ends. The foundation preferably forms a stop for the toggle bar when the toggle members have become fully expanded. In this position the pivot centers of the toggle members of a set will be in alignment and the toggle sets will be thus 25 self-locked in expanded position. The ring 22 with its flange 22^a besides serving as an abutment for the mold frame and core shell, acts also as a core to form the abutment shoulder 24 and the joint flange 25 in the 30 pipe which is cast in the mold. After the core shell has thus been inserted and expanded, the concrete or other cement material 26 is poured in and the pipe formed. If desired suitable metallic reinforcing material may be inserted between the core and 35 mold frame before pouring.

After the poured material becomes sufficiently set the core shell is withdrawn. The bar 18 is first drawn outwardly, and as the 40 links 15 of the toggle sets are anchored to the shell, the toggle links when swung upwardly by the rising toggle bar will cause movement of the bar toward the T-bar 13 and withdrawal of the wedge channel 14 from the shell ends, the shell being then free 45 to collapse so that upon further upward movement of the toggle bar the shell will follow and will be withdrawn. The shell will, however, stick more or less to the cement surface and in order to forcibly withdraw the shell from the cement pipe before the shell is raised, sets of chains or cables 50 27 and 28 are anchored to the toggle bar by means of clevises 29 and connected at their 55 outer ends to lugs 30 and 31 secured to the core shell adjacent its ends. The connection of each set of chains with the toggle bar is a distance below the connections of the chains with the shell when the toggle members 60 are expanded so that when the toggle bar is raised the chains will be slack for a period and will not exert pull on the shell ends until the toggle bar has been raised sufficiently to effect withdrawal of the wedge 65 channel from between the shell ends (see

Fig. 3.) Upon further upward movement of the toggle bar the chains will then pull on the shell ends and the links 15 will pull on the T-bar 13 secured to the middle of the shell, the result being that the shell will be 70 powerfully drawn together and away from the cement surface to be entirely free from such surface before the shell will start to rise. When the core structure is suspended free of the mold its shell will be fully collapsed and it can be readily inserted into another mold frame and into the ring 22 on the foundation. After removal of the core structure the mold frame can also be removed and the finished pipe taken from the 75 foundation.

It is important that the other face of the channel wedge register accurately with the outer surface of the shell when the core is expanded as otherwise it might be impossible to collapse the core after the molding operation and the pipe would not be accurate. In order to assure proper alignment, stop members 32 are provided at intervals on the wedge channel, these stop frames being of U-shape and having their yokes riveted or otherwise secured to the inner face of the channel and having the ends turned outwardly to form hooks 33 for engaging about the inner edges of the 80 flanges 11' and 12' of the angle bars as soon as the outer face of the channel comes into register with the outer surface of the shell. Overthrow of the channels by the toggle members is thus prevented. The hook ends 85 33 also prevent over-expansion of the shell. As a further precaution against relative displacement between the shell ends and the wedge channel locking pins 34 are provided for engaging in holes 35 and 36 in the 90 flanges 11' and 12' respectively to abut against the inner edges of the wedge channel flanges, the angle bars 11 and 12 and therefore the shell ends being thereby prevented from outward displacement relative to the 95 wedge channel. In the smaller sized core structures such pins may not be necessary but in the sizes which are large enough to allow entrance of a workman such pins are 100 preferably used to prevent displacement 105 and they can readily be inserted in place after the toggle members have been expanded so that the shell will be absolutely rigid during the pouring operation. After the 110 pouring operation the pins are withdrawn 115 and the shell is then free to be collapsed and withdrawn from the mold. I thus provide an all metallic core structure which can be 120 quickly inserted and withdrawn from a mold frame and which is automatically expanded when inserted in the mold frame and automatically collapsed upon withdrawal therefrom, the toggle mechanisms 125 exerting powerful force to operate the wedge member and the chains positively ef- 130

fecting collapse of the shell and withdrawal thereof from the mold surface.

Although the core structure has been shown and described in connection with a 5 mold frame for forming pipe or conduit, it is evident that the core structure could be used for progressive construction of concrete conduit work. The core shell could be laid directly on a concrete foundation in 10 the trench in which duct is to be formed and the concrete material for the sides and top of the duct applied thereto. Then when one length of concrete becomes sufficiently set 15 the core will be collapsed by pull on the toggle bar and can be shifted forwardly over the next section of foundation and the next side and top duct section formed, and so on, the duct being built up progressively.

I do not desire to be limited to the exact 20 construction, arrangement and operation shown and described as changes and modifications are no doubt possible which would still come within the scope of the invention as claimed.

25 I claim the following:

1. In a collapsible core, the combination of a sheet metal shell bent into substantially circular form to bring its ends in opposition, a wedge bar within the shell and parallel 30 with said ends, toggle links pivoted at their outer ends to said shell substantially midway between its ends, companion toggle links pivoted at their outer ends to said wedge bar, a toggle bar extending into said 35 shell, the inner ends of said toggle links being pivoted to said toggle bar whereby upon movement of said bar said toggle links are actuated to insert the wedge bar between the shell ends or to withdraw said bar from 40 said ends, and pull chains connected to said bar and shell ends for effecting radial pull on said ends after said toggle bar has been moved a distance to effect withdrawal of said wedge bar from said ends.

45 2. In a collapsible core, the combination

of a metallic shell bent into substantially cylindrical form with its ends in opposition, wedge flanges extending inwardly from said ends, a wedge member in the form of a channel bar arranged within said shell with 50 its flanges extending inwardly, a toggle bar extending into said shell, toggle links connecting with said toggle bar and with the shell substantially mid-way of its ends, companion toggle links connecting with said 55 toggle bar and with said wedge member, hook extensions from said wedge member for engaging about the inner edges of said wedge flanges to limit the outward movement of said wedge member between said 60 flanges.

3. In a collapsible core, the combination of a metallic shell bent into substantially cylindrical form with its ends in opposition, wedge flanges extending inwardly from 65 said ends, a wedge member in the form of a channel bar arranged within said shell with its flanges extending inwardly, means for forcing said wedge member between the wedge flanges to spread the shell, hook extensions from said wedge member for engaging about the inner edges of said wedge flanges to limit the outward movement of the wedge member between said flanges, the opposed wedge flanges having openings, and 70 locking pins extending through opposite holes and abutting against the inner edges of the wedge member to prevent inward movement of said wedge member after outward movement thereof between said wedge 75 flanges, said hook extensions and pins co-operating to hold the outer face of the wedge member in alinement with the outer surface of the shell.

In witness whereof, I hereunto subscribe 80 my name this 20th day of January, 1913.

CHARLES F. MASSEY.
